UNITED STATES PATENT OFFICE.

WILLIAM W. DAVIDSON, OF SPRINGFIELD, OHIO, ASSIGNOR TO THE RIDGELY TRIMMER COMPANY, OF SPRINGFIELD, OHIO, A CORPORATION OF OHIO.

WIRE BRUSH.

Application filed May 4, 1925. Serial No. 27,734.

This invention relates to an improvement in a wire brush which is capable of being inserted within openings or ports for cleaning parts located within said openings or ports; that is, parts that are not readily accessible for the ordinary scraping or cleaning tool, such as the inside edges of the valve seats of motors and similar devices.

Heretofore difficulty has been experienced with brushes of this general character because they were not adapted to work properly within openings or ports of different sizes, such as are encountered in motors of different makes, and also because the wires were not readily renewable and would not withstand the severe use given them in such kinds of work, and did not operate satisfactorily on parts within openings such as the inside edges of valve seats or similar parts.

In a general way this improvement consists preferably of twisting the wires of the brush into a tuft of wires, which is specially designed in a manner like that described in Letters Patent No. 1,493,670, the tuft of wires being securely attached to a two part support which is combined with an enclosing member that is adapted in normal position to insure the tuft of wire being held securely attached to said support, and permitting ready renewal of the wire.

Referring to the drawings:

Fig. 1 is a view in side elevation of the wire brush tool.

Fig. 2 is a central longitudinal section.

Fig. 3 is a similar view to Fig. 1, the parts being given a quarter turn, showing parts in section.

Fig. 4 is a transverse sectional view on the lines 4-4 of Fig. 1.

Like letters of reference indicate like parts throughout the different views.

Referring to the drawings, 1 indicates a cylindrical support having a projecting stem 2 and the stem 2 is arranged to be connected with the chuck C of any suitable power machine for imparting a rotary movement to the brush. The cylindrical support 1 is formed with a shoulder 3 at its upper end and also a groove 4 (see Fig. 4). On the opposite side of this cylindrical support 1 and at its other end is a tapered surface marked 5. The elongated holding member 6 which is preferably of metal that

can be sprung into place is adapted to fit within the groove 4 and the upper end of the elongated member 6 has a bent end 7 which is adapted to be snapped into engagement with the shoulder 3. The lower end 8 of the elongated member marked 8 is hook-shaped and extends against the inclined surface 5 so that by pressing the elongated member 6 upwardly the hooked end 8 will slide along the inclined surface 5 and the end 7 can then be snapped into engagement with the shoulder 3. As indicated in Figs. 2 and 3 the tuft of wire 9 is twisted into such form that the twisted ends 10 of the wires can be threaded upon the hooked end 8 of the elongated member 6, and by disconnecting the elongated member 6 from the cylindrical member 1 the twisted wires can be removed and new wires inserted. This is especially desirable where the tool is given such severe use that by reason of heat or friction the free ends of the wires become welded or matted together so as to destroy the efficiency of the brush, requiring the wires to be renewed frequently.

There is also employed a sleeve member 11 (Fig. 1) and this member is adapted to enclose the lower part of the cylindrical member 1 and the elongated member 6, thereby insuring that the parts will be held snapped together in proper position. This sleeve 11 is secured to the cylindrical support 1 by the set screw 12 (Fig. 1) which set screw passes through a slotted opening 13 formed in the central part of the sleeve 11 and projects within a corresponding opening in the cylindrical support 1; the walls of the opening being provided with a series of countersunk seats 14 for the head of the set screws to prevent slippage of the sleeve. As shown in Fig. 1 this sleeve is adjustably mounted by reason of the fact that there are a plurality of openings formed in the sleeve so that the set screw 12 can be removed from the position shown in Fig. 1 and the sleeve thereupon be slid upwardly and the set screw then placed within a different opening.

It is apparent that so long as the sleeve 11 encloses the lower part of the elongated member 6 of the cylindrical support 1, the elongated member cannot be readily moved in its relation to the cylindrical support 1, so that the parts will be held locked and the tufts of wire cannot be removed from

the elongated support until the sleeve is moved sufficiently to expose the hooked end 8 of the elongated member. Furthermore, by moving the sleeve 11 in its relation to the two part support 1—6, the proper adjustment can be made to render the tool suitable for different openings, in the head of a motor. If the opening is small, the wires must be more compactly arranged and therefore, the sleeve 11 is slid to its lower-most position, while if the opening is a large one the sleeve is slid to its upper position, thereby allowing the wires to fit more satisfactorily within a large opening.

Having thus described my invention, I claim:

1. In a device of the character described, the combination of a cylindrical supporting member, said supporting member being provided at one end with an inclined surface and also provided with an intermediate shoulder, a rod-like holding member of metal having one end formed for engagement with said shoulder and the other end provided with a hook-shaped portion to receive tufts of wire, the free end of said hook-shaped portion being engageable with said

inclined surface, and a sleeve member slidably mounted upon said supporting member and embracing said holding member and extending beyond the inclined end of said supporting member to embrace a portion of the tufts of wire.

2. In a device of the character described, the combination of a cylindrical supporting member, said supporting member being provided on one side of one end thereof with an inclined surface and on the opposite side with a longitudinally extending groove, a shoulder being formed in said member at the upper end of the groove, a rod-like holding member of metal having one end formed for engagement with said shoulder and the other end provided with an open hook-shaped portion to receive tufts of wire, the free end of said hook-shaped portion being engageable with said inclined surface, and a sleeve member slidably mounted upon said supporting member and embracing said holding member.

In testimony whereof, I have hereunto set my hand this 30th day of April, 1925.

WILLIAM W. DAVIDSON.
